UNITED STATES PATENT OFFICE.

ARTHUR L. VALPEY, OF ILION, NEW YORK, ASSIGNOR TO REMINGTON ARMS COMPANY, INC., A CORPORATION OF DELAWARE.

CASH REGISTER.

Application filed September 22, 1923. Serial No. 664,222.

This invention relates to improvements in cash registers and has more particular relation to improvements in the engaging mechanism for totalizers.

5 One of the objects of the present invention is to provide improved means for preventing an engagement between the totalizer and the operating mechanism whenever one of a plurality of special keys is operated. 10 Still another object of the present invention is to prevent any accidental or intentional movement of the totalizer when it is adjusted so as to prevent a co-operative relationship between the wheels and their 15 related operating mechanism. The illustrative embodiment is further provided with mechanism for preventing any fraudulent operation of the totalizer disengaging mechanism after a registration of an item 20 has commenced.

For the purpose of illustration the present invention is shown applied to the type of cash registers shown and described in the Letters Patent, issued to Thomas Carney, 25 dated May 23, 1893, #497,860, and to E. J. Von Pein, #1,371,653 dated March 15, 1921. This embodiment is illustrative only as the improvements are capable (either with or without modification and change) of application to machines of other types and it is 30 the desire not to be limited in the form of embodiment herein shown and described.

With these and incidental objects in view, the invention consists in certain novel features of construction and combination of parts, a preferred form of embodiment of which is hereinafter described and reference to the drawings which accompany and form part of the specification.

40 Of said drawings:

Fig. 1 is a transverse sectional view of a cash register of the type shown and described in the patents to Carney and Von Pein with the various novel features applied thereto.

Fig. 2 is a top plan view of the mechanism detached from the machine frame, and shows the connections between the totalizer disengaging mechanism and the special keys 50 for controlling the same.

Described in detail the machine comprises a series of amount keys 15, and a plurality of transaction keys 16. All of the keys associated with the two classes just referred to

are pivoted at their central portions upon 55 a transverse rod 17 suitably journaled in the side frames of the machine.

Resting upon the rear ends of the amount keys 15 is a key coupler 18 which is journaled at 19 in the side frames and is provided 60 with a nose 20 adapted to co-operate with notches 21 formed in the rear ends of the keys. From the above construction it is evident that when the outer ends of the keys are depressed the nose 20 of the coupler will 65 enter the notches 21 of the depressed keys.

Connected to the key coupler 18 is a double rack bar 22 provided with rack teeth 23 which co-operate at the desired time with the teeth of a pinion 24 secured to a drive 70 shaft 25. As the coupler 18 is rocked by an operation of the keys, the rack is raised and lowered, the rack teeth alternately engaging the teeth of the pinion 24. The result of the above construction is that a complete reciprocation of the coupler 18 will 75 effect a complete rotation of the shaft 25. The shaft 25 carries cams and other devices for operating various parts of the mechanism. The mechanism for effecting a complete rotation of the shaft is neither shown nor described in detail since it is old and well known in the art. However, for details of construction and operation reference may be had to the patent issued to Thomas Carney, #497,860, May 23, 1893. 80

The series of keys 16, which have been hereinbefore designated as transaction or "throw-out" keys are of a different construction than the amount keys 15 and substantially of the construction shown and described in the patent to E. J. Von Pein, #1,371,653, dated March 15, 1921. For a fuller and more complete description of the operation of these keys reference may be 95 made to this patent.

The transaction keys are so constructed that they may be given a slight preliminary depression and held in their depressed position by suitable locking devices. This preliminary movement of the keys will have no effect upon the main operating mechanism and will bring into operation certain mechanism associated with the totalizer engaging mechanism so that upon a further depression of the transaction key and amount keys, the totalizer will be held in its disengaged position and the amount entered in the ma- 105

chine will not be inserted in the totalizer. The keys 16 have their upper rear edges cut away as at 26 so that the keys may be given an initial depression without moving the 5 coupler 18. As is the case with the amount keys 15 the special keys 16 are provided with notches 27 to co-operate with the nose 20 of the coupler 18.

The rear end of each transaction key is 10 provided with a pair of pawls 28 and 29 the normal positions of which are substantially that shown in Fig. 1. The pawl 28 is pivoted upon the rear end of the key at 30 and is normally held against the frame portion 31 15 by a spring 32 interposed between a stud 33 and the forward edge of the pawl. The pawl 28 is provided with a hook end 33 adapted to co-operate with a locking point 34 of the pawl 29 as will hereinafter be described.

20 When any one of the keys 16 is depressed the rear end of the key will be elevated sufficiently until the lower end of the pawl 28 passes clear of the frame portion 31, when under the action of the spring 32, the lower 25 end of the said pawl will move rearwardly above the frame portion 31. In this manner the transaction keys will be held in their partially depressed positions.

As the rear end of the depressed key 30 moves upward the upper edge 35 of the pawl 29 will strike the underside of the nose 20 of the coupler 18 and during a continued depression of the keys the pawl 29 will be rocked counter-clockwise about its pivot 37 35 carrying the point 34 away from the hook 33 of the pawl 28 and bringing the upper edge 35 across the notch 27 in the depressed transaction key.

This initial depression of any of the transaction keys will, when the rear end of the key is elevated, cause the point 38 which is at the outer end of the notch 27 to cross the arc of movement of the rear edge of the nose 18 of the key coupler, consequently when 45 the coupler 18 is rocked counter-clockwise about its pivot 19 the nose 20 will engage the point 38 at the outer end of the notch 27 of the transaction keys 16 and upon the continued movement of the coupler 18 under 50 the control of the amount keys 15 the rear end of the partially depressed transaction keys 16 will be carried upward with the key coupler 18 thereby completing the operation of the previously partially depressed key.

55 As this operation takes place the nose 20 of the coupler 18 will enter the notch 27 of the depressed transaction key and engage the upper edge 35 of the pawl 29. During the continued operation of the key coupler 60 18 the pawl 29 will be rocked clockwise about its pivot 37 until the point 34 of the pawl 28 will be brought into position adjacent the hook 33 of the pawl 28. At this time the pawl 28 will have passed free of the 65 frame portion 31, the spring 32 being effec-

tive to rock the pawl 28 about its pivot 30 in a counter-clockwise direction causing the hook portion of the pawl 28 to engage and lock over the point 34 of the pawl 29. This will hold the upper edge 35 of the pawl 29 70 rigid against the underside of the nose 20 of the coupler 18.

When the transaction and amount keys have completed their movement in one direction, by virtue of the weight of the coupler and associated parts the keys will begin 75 their upward or negative stroke.

As the key coupler rests upon the amount keys this downward or clockwise movement of the coupler 18 will be applied directly 80 to these keys, and since the cut-away portion 26 of the transaction keys does not permit of the key coupler directly contacting with the said keys, the nose 20 resting upon the upper edge 35 of the pawl 29 will perform 85 the function of restoring the transaction keys to their normal position.

As the transaction keys reach their normal position a beveled rear face 39 formed on the lower end of the pawl 29 will engage 90 the curved edge 40 of the frame portion 31 and upon the continued restoring movement of any transaction keys 16 the pawl 28 will be rocked about its pivot 30 thereby disengaging 95 the hook portion 33 from the point 34 of the pawl, the parts then being again in the position shown in Fig. 1. The construction and operation of the above mechanism is the same as that of patent, to Von Pein, 1,371,653 referred to.

100 As shown and described in detail in the patent to Carney the amount keys are arranged in series or banks of different denominational order. Associated with the keys relating to a particular bank is a registering frame carrying a registering segment which engages at the desired time a 105 totalizer element corresponding to the bank of keys which operate upon the registering frame. Since the differential mechanism is 110 alike for the different denominational orders a description of one will suffice for all.

115 Each key 15 related to the cents bank has pivoted at its rear end a lifting plate 41 formed with a recessed portion 42 which engages a transverse bar 43 carried by the cents registering frame 44. Secured to the registering frame 44 is a registering segment 45, the teeth of which engage at the proper times the pinion 46 of the cents totalizer wheel 120 47. The slots 42 in the plates 41 are graduated so that they will cause the registering segment to give the totalizer wheel a differential movement corresponding to the 125 value of a depressed key. The manner in which these parts cooperate is well known and fully described in detail in the Carney patent.

130 The totalizer shown in the illustrative embodiment is substantially the type shown

and described in the patents to A. W. Marr, #570,178 and #570,196 dated October 27, 1896. The six totalizer elements 47 and 48 are in the form of wheels rotatably mounted in a shaft journaled in a rocking totalizer frame 49. The totalizer frame is pivoted at its lower end at 500 and is adapted to be rocked during each operation of the machine.

- 10 The mechanism whereby the totalizer elements are thrown into engagement with the operating segments will now be described. Pivottally mounted upon the right hand side of the totalizer frame at 50 is a totalizer engaging lever 51 slotted at 58 to receive the pivot stud 500 and carrying at its rearward end a pair of rollers 52 in engagement with a cam 53 secured to the rotation shaft 25. The forward end 54 of the totalizer engaging lever rests just beneath and in direct contact with a transverse lug 55 formed upon a member 56 slidably mounted and carried by the totalizer frame 49. The lug 55 in turn is in immediate contact with a stud 57 carried by the totalizer frame 49.

The result of the above construction is that whenever the shaft 25 is rotated by a depression of the amount keys the rollers 52 carried by the lever 51 will co-operate with the cam 53 and force the forward end 54 of the counter engaging lever upward. Since the forward end 54 is in immediate contact with the lug 55 on the member 56 carried by the totalizer frame and since the lug contacts with the stud 57 secured to the totalizer frame, the upward movement of the lever 51 will rock the totalizer pinions into engagement with the operating segments 45.

40 The totalizer pinions are thrown into engagement with the segments before any movement of the registering segments is begun. This engagement continues during the downward stroke of the outer ends of the keys. At the completion of the downward stroke of the keys the cam 53 will act upon the rollers 52 and depress the forward end of the totalizer engaging lever 51 whereby by virtue of the engagement between the pivot stud 500 and upper end of the slot 58 the lever will rock the totalizer pinions out of engagement with their corresponding racks. During the return movement of the keys the pinions will remain disengaged, so that the return movement of the segment racks will have no effect upon the totalizer elements.

45 Certain of the keys 16 referred to hereinbefore have been designated as "transaction" keys, and as shown in Fig. 2 these keys are the "Paid out" and "Charge" keys. In order to have the totalizer accumulate only the money received by the various clerks it is desirable that these keys, which do not involve the receipt of cash, throw-out the totalizer whenever anyone of these keys is oper-

ated in conjunction with the amount keys. The novel means for accomplishing the desired results will now be explained.

As previously stated the forward end 54 of the totalizer engaging lever 51 is in engagement with a lug 55 on a slidable member 56. The member 56 is guided in its reciprocatory movements by studs 60 and 61 secured to the totalizer frame 49. A coil spring 62 interposed between the totalizer frame 49 and a spring stud secured to the slide 56 tends to move the slide forwardly from the position shown in Fig. 1. The slide 56 is provided with a cut-away portion 63 the purpose of which will appear hereinafter.

The slide 56 is prevented from moving forwardly under the influence of the spring 62 by a stud 64 carried by a movable stop member 65 pivoted upon the key shaft 17. The member 65 is secured at 66 to an upstanding bail comprising two side members 67 and 68 and a cross bar 69. This bail in turn is secured to a second bail comprising two side members 70 and 71 and a cross bar 72. Due to the fact that certain mechanism is placed beneath the key shaft 17 between the side members 67 and 68 it was necessary to construct the bail mechanism so that the cross bar 69 would be above the key shaft 17 thereby avoiding interference with other parts of the register mechanism.

Placed adjacent and associated with each throw-out key is a bail operating plate 73 pivoted upon the keyshaft 17. Each bail operating plate 73 is provided with a lug 74 contacting with the lower edge of a key 16 and has further a downwardly extending projection 75 bearing against the forward edge of the bail 72. A spring 76 is interposed between the bail 72 and the frame of the machine, the tension of this spring being sufficient to overcome the tension existing in the spring 62, thereby retaining the relationship between the stud 64 and the slide 56 substantially as that shown in the drawings as premised hereinbefore. When the parts are in this position the totalizer will be thrown into engagement with the operating segments during the first movement of the amount keys 15.

Whenever a throwout key 16 is depressed to its partially depressed position the parts will be adjusted so that upon a depression of the amount keys a co-operative relationship between the totalizer pinions will be prevented. The manner in which this is accomplished will now be described.

When ever a throwout key 16 is depressed a slight amount the pawl 28 contacting with the portion 31 of the frame will retain the operated key in its depressed position. During the time that the key was depressed the engagement of the lug 75 with the forward edge of the bail 72 will rock the said bail as well as the bail 69 counter-clockwise

as viewed in Fig. 1. The rocking movement of the bail will be imparted to the movable stop member 65 carrying the stud 64 forward, thereby permitting the spring 62 to draw the slide 56 forwardly. When in this operated position the lug 55 occupies a position just forward of the lug 54 of the totalizer engaging lever, the cutaway portion 63 of the slide 56 now being directly over the end 54. It is of course understood that no movement of the shaft 25 or coupler 18 takes place during this preliminary movement of a transaction key.

Upon a depression of any amount key 15 the forward end 54 of totalizing engaging lever 51 will be elevated but will have no effect upon the totalizer frame since the lug 55 has been withdrawn and the end 54 will merely play idly in the cut-away portion 63. 20 To permit of the movement of the totalizer engaging lever 51 without affecting any movement of the totalizer frame the said lever is provided with the enlarged aperture 58 surrounding the pivot shaft 500 of 25 the totalizer as stated hereinbefore.

It is desirable that means be provided to prevent the totalizer from falling into mesh either by its own weight or by the application of force when the totalizer is to remain 30 unoperated during an operation of the machine. In order to preclude this possibility the member 65 is provided with an upper edge 77 which is concentric to the key shaft 17. When the stop member 65 is partly or 35 fully forward the stud 61 will be directly over the concentric edge and the totalizer will thus remain locked until the keys have been restored to normal.

Means are further provided for preventing 40 any operation of the totalizer throwout mechanism after the keys begin to operate. Just forward of the concentric edge 77 just referred to is a locking notch 78. When the totalizer is thrown into mesh the stud 61 45 will enter the locking notch 78 thereby preventing any movement of the stop member 65 or parts attached thereto. Due to this construction it will be impossible to actuate any part of the totalizer throwout mechanism 50 after the registration of an item has begun.

While the embodiment herein shown and described is well adapted to fulfill the objects above stated, it is not the intention to 55 limit the invention to the one form, as it is capable of various modifications and changes all coming within the scope of the claims which follow.

What is claimed is:—

10 1. In a cash register comprising amount keys and differential mechanism controlled thereby, the combination of a totalizer frame and totalizer elements carried thereby, a lever for engaging the totalizer elements 15 with the differential mechanism during an

operation of the machine, a slidable member mounted on said totalizer frame and adjustable in the plane of said lever capable of rendering the lever ineffective to engage the totalizer elements with the differential mechanism and spring means tending to move the adjustable member to a position to render the said lever ineffective. 70

2. In a cash register, comprising amount keys, special keys, and differential mechanism controlled by said amount keys, in combination, a totalizer frame and totalizer elements carried thereby, a lever for engaging the totalizer elements with the differential mechanism during an operation of 80 the machine, a slidable member mounted on said totalizer frame and adjustable in the plane of said lever, capable of rendering the lever ineffective to engage the totalizer elements with the differential mechanism, 85 spring means tending to move the adjustable member to a position to render the said lever ineffective, and means whereby the operation of said special keys permits the said spring means to become effective. 90

3. In a cash register, comprising amount keys, special keys, totalizer elements and means controlled by the amount keys for actuating the totalizer elements, in combination a lever operated during each operation 95 of the machine for engaging the totalizer elements with the said means, a member provided with a lug normally in engagement with one end of the said lever but adjustable in the plane of the lever, spring 100 means tending to move the adjustable member from its normal position, a movable stop member preventing the operation of the spring means, and devices under the control of the special keys for moving the said stop member thereby permitting the spring means to disengage the said lug from the lever and preventing an engagement of the totalizer elements with the first recited means. 105

4. In a cash register, comprising amount 110 keys, special keys, a totalizer frame and totalizer elements carried thereby, and a differential mechanism, in combination, a lever operated during each operation of the machine for engaging the totalizer elements 115 with the differential mechanism, an adjustable member movable to different positions for controlling the effectiveness of the lever for totalizer engagement, tensioning means for moving the said adjustable member, a pivoted member having means for preventing the operation of the said tensioning means, a bail connected to the pivoted member, and means associated with each special key for operating the bail and pivoted member 120 thereby permitting said tensioning means to move the adjustable member to a position wherein the lever will be ineffective for totalizer engagement. 125

5. In a cash register, comprising amount 130

- keys, special keys, a totalizer frame and totalizer elements carried thereby, and a differential mechanism, in combination, a lever operated during each operation of the machine for engaging the totalizer elements with the differential mechanism, an adjustable member movable to different positions for controlling the effectiveness of the lever for totalizer engagement, tensioning means 5 for moving the said adjustable member, a pivoted member carrying a stud in engagement with the adjustable member for preventing the operation of said tensioning means, a bail connected to the pivoted member, a second tensioning means for holding the bail in its normal position and means associated with each special key when operated for operating the bail and pivoted member thereby withdrawing the stud and 10 permitting the first said tensioning means to move the adjustable member to a position wherein the lever will be ineffective for totalizer engagement.
6. In a cash register, comprising a totalizer frame and totalizer elements carried thereby, amount keys, and a differential mechanism under control of the amount keys, in combination, a lever carried by the 15
- 20
- 25

totalizer frame for engaging the totalizer elements with the differential mechanism 30 during an operation of the machine, a slide carried by the totalizer frame capable of movement parallel to said lever for rendering the lever ineffective to engage the totalizer elements with the differential mechanism, and spring means tending to move the slide to a position to render the said lever ineffective.

7. In a machine of the class described a rocking frame, a totalizer mounted therein, 40 differential actuators for said totalizer normally disengaged therefrom, a lever operated upon each operation of the machine for rocking said totalizer into engagement with the actuators, a spring tensioned slide 45 adjustable in a plane parallel to said lever to determine the effectiveness of said lever, and a key controlled member provided with a stud to determine the position of adjustment of said slide, said member including 50 means to prevent rocking of said frame when the slide is adjusted to render the lever ineffective.

In witness whereof I have signed my name this 20th day of September, 1923.

ARTHUR L. VALPEY.
